TABLET ARM CHAIR

Russel Wright, New York, N. Y., assignor to Shwayder
Brothers, Ecorse, Mich., a corporation of Colorado

Application February 24, 1955, Serial No. 34,656

Term of patent 14 years

(Cl. D15—1)

Fig. 3

Fig. 1 is a perspective view of a tablet arm chair showing my new design;

Fig. 2 is an enlarged top plan view of the tablet arm member and support therefor; and

Fig. 3 is an enlarged fragmentary side elevational view illustrating the tablet arm member and support therefor, the seat element and a portion of one of the leg members.

I claim:

The ornamental design for a tablet arm chair, substantially as shown.
